COMBINATION VENETIAN BLIND, DRAPERY RAIL, AND CORNICE MOUNT

David Jordan Rust, San Leandro, Calif., assignor to Ry-Lock Company, Ltd., a corporation of California

Application May 2, 1939, Serial No. 271,272

7 Claims. (Cl. 156—17)

This invention relates in general to window shade and drape mounting, and in particular the invention is directed to a combination Venetian blind, drapery rail and cornice mount.

At present it is the custom to secure the Venetian blind on a window independently and prior to the mounting of the drapery rail, and the enclosing cornice; the drapery rail being mounted either within the cornice or directly on the window. This requires a multiplicity of operations with the treatment of each window, resulting in undue loss of time and relatively high installation costs.

It is therefore the principal object of my invention to provide a combination mount for an "outside hung" Venetian blind, and the associated drapery rail and cornice.

Another object of the invention is to provide a mount of the type described including a single supporting member on which the drapery rail is permanently secured, and on which the Venetian blind and cornice are adapted to be readily and removably attached; the supporting member being adapted to first be secured on a window and the Venetian blind and cornice subsequently attached.

An additional object of the invention is to provide a combination Venetian blind and cornice mount wherein the cornice is not only removably attached but is adjustable lengthwise whereby to position the cornice properly relative to the Venetian blind.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Figure 1 is a front elevation of the mount; a portion of the cornice being removed.

Figure 2 is a foreshortened perspective view of the mount; the Venetian blind and a portion of the cornice being removed.

Figure 3 is an enlarged cross-section on line 50 3—3 of Fig. 2.

Referring now more particularly to the characters of reference on the drawings, the mount comprises a horizontal head board 1 which is of substantial width and at least as long as the width of the Venetian blind to be supported

therefrom as will hereinafter appear. This head board is fixedly secured in horizontal position outside a window by means of suitable right angle brackets 2 on the window casing.

A Venetian blind of the combination head and tilt rail type, and including a rail 3, tapes 4, slats 5, cord lock 6, raising cord 7 and tilting cord 8, is removably supported beneath head board 1. The supporting means comprises slotted end brackets 9 and 10 depending from the head 10 board, and cooperating pins 11 and 12, respectively, projecting from the ends of rail 3 and releasably engaged in the bracket slots.

The bracket 10, including a face plate, carries a worm gear 13, which is rotated from a pulley 15 14 over which cord 8 runs, and which worm gear disengageably meshes with a segmental gear 15 on the adjacent end of rail 3. A latch arm 16 on bracket 9 prevents accidental escape of pin 11 from the slot therein.

A drapery rail, preferably in two sections 17, extends lengthwise of the head board some distance therebelow and is disposed in a vertical plane in front of the plane of the front edge of said board. The outer ends of the sections curve 25 rearward as at 18 and extend in a plane beyond the brackets 9 and 10 to a termination short of the window casing. The sections are metal strips and have inturned ears 19 on their ends to prevent the drapery hooks from escaping from 30 the sections. Each section is secured in connection with the head board by means of a number of inverted right angle brackets 20; such brackets being riveted at one end on the drapery rail sections, as at 21, while the other end is fixed on the 35 under surface of the head board by screws 22. The brackets 20 are fixed on the head board in such position that the horizontal arm of each such bracket extends some distance beyond the front edge of the board whereby to form ledges 23, whose purpose will hereafter appear.

The cornice includes the usual front or facia panel 24 and end panels or returns 25; such cornice being of a length and width to surround or shield the head board, the upper end or tilt rail 45 portion of the Venetian blind, the supporting and operating mechanism therefor, and the sections of the drapery rail. A longitudinal cleat 26 is secured on the back of the cornice front panel 24 at the upper edge thereof, such cleat 50 being substantially the same thickness as head board 1 and of a materially greater width than the projecting extent of ledges 23. When the cornice is disposed in proper position, the cleat 26 rests on ledges 23; the cornice being held 55

against forward displacement by spaced hooks 27 fixed on the cleat and removably engaging in a narrow but deep groove 28 cut in the top of board 1 and extending lengthwise thereof. As 5 the groove is of greater length than the spacing of the hooks, the cornice can be moved longitudinally to adjust the same.

To install the above described mount, the Venetian blind and cornice are detached and the 10 head board 1 is mounted in place; such being accomplished with ease due to the light weight and relatively small bulk of the head board and fixed elements thereon. The Venetian blind is then attached to brackets 9 and 10, and thereafter the drapes are suspended from the drapery rail sections 17. Finally, the cornice is attached by engagement of hooks 27 in groove 28 and with cleat 26 resting on ledges 23.

As so mounted, all of the working parts are 20 out of sight, and yet are readily accessible for cleaning or repair. Also, the cornice, drapes, and Venetian blind can be manually detached quickly and without the use of tools and as is desirable for cleaning purposes.

25 While the hereinbefore described combination is particularly intended to include outside hung Venetian blinds, inside hung Venetian blinds may be likewise included in the combination.

From the foregoing description it will be readily 30 seen that I have produced such a device as substantially fulfills the objects of the invention as set forth herein.

While this specification sets forth in detail the present and preferred construction of the device, 35 still in practice such deviations from such detail may be resorted to as do not form a departure from the spirit of the invention, as defined by the appended claims.

Having thus described my invention, what I 40 claim as new and useful and desire to secure by Letters Patent is:

1. In combination, a head board adapted to be mounted on a window casing with the upper surface of said board exposed, a plurality of 45 longitudinally spaced members fixed on the board and projecting forward below said upper surface and whereby to form ledges, a cornice including a front panel, a longitudinal cleat fixed on the back of the panel, such cleat being adapted to 50 abut against the front edge of the head board and to rest on said ledges, and hooks secured on the upper surface of the cleat and overlying the head board when the cleat is so positioned; said head board having a socket portion into which the hooks removably engage.

2. An assembly as in claim 1, in which the 55 front edge of the head board and the abutting edge of the cleat are of substantial width; the ledge forming members being fixed on and projecting from the bottom of the head board.

3. An assembly as in claim 1 in which the ledge

forming members comprise inverted L shaped brackets; there being a horizontal drapery rail secured on and supported by the depending arms of said brackets.

4. In combination, a head board adapted to be 5 mounted on a window casing, a drapery rail disposed below the head board, supporting brackets connected between the head board and rail, a portion of said brackets forming longitudinally aligned, horizontal ledges, a cornice having a 10 front panel, a longitudinal cleat fixed on the back of said panel and adapted to rest on said ledges, and releasable means connected between the cornice and head board and arranged to prevent forward displacement of the cleat relative 15 to the ledges.

5. In combination, a head board adapted to be mounted on a window casing with the upper surface of said board exposed, a cornice, and means 20 removably mounting the cornice on the head board; said means including longitudinally spaced connecting elements fixed on the cornice and overlying said surface of the head board, there being downturned fingers on the overlying 25 ends of the elements, and the head board having a longitudinal groove into which said fingers engage, the groove being of greater length than the distance between the most remotely spaced elements whereby the cornice may be adjusted lengthwise relative to the head board.

6. In combination, a head board adapted to be mounted on a window casing with the upper surface of the board exposed, a separate cleat extending substantially the full length of and abutting against the front edge of the head board, 35 the abutting edges of the head board and cleat being of substantial width, a cornice panel fixed on and depending from said cleat, and means quickly detachably connecting said cleat with the head board; said means including a plurality of 40 longitudinally spaced elements mounted on the upper surface of the cleat and overlying the upper surface of the headboard, and downturned fingers on the overlying ends of said elements, the headboard having recesses into which said 45 fingers hookingly engage.

7. In combination, a head board adapted to be mounted on a window casing, a cornice panel disposed in front of the head board, a longitudinal cleat fixed on the back of the panel, the adjacent edges of the head board and cleat being of substantial width and abutting, means associated with the head board and forming ledges immediately below and projecting outwardly from said abutting edges, the under surface of the 55 cleat adjacent said edges resting on said ledges, and hooks secured on the upper surface of the cleat and overlying the head board when the cleat is so positioned, said head board having a socket portion into which the hooks removably engage. 60

DAVID JORDAN RUST.
